ELECTRICAL CONNECTOR

Chester E. Pieper, Warrenton, Mo.

Application June 9, 1943, Serial No. 490,390

5 Claims. (Cl. 173—273)

My invention relates to improvements in electrical connectors and more particularly to an improved device of this character which is especially adapted for connecting a tap wire to an overhead line while the latter is energized.

The principal object of the invention is to provide an improved wire connector of this type which can be made smaller, lighter, with fewer parts and less metal than former types of so-called hot-line clamps, yet which is superior to these earlier devices in facility of installation, durability and operating efficiency.

This object is attained by improvements in the form and arrangements of the several operating parts whereby both tap and line wires are clamped between a single pair of jaw elements operated by a single clamping nut; whereby the jaws are adapted to adjust themselves to wires of various size combinations, and extremely high clamping pressures are obtained with moderate turning force applied to the nut. A further improvement resides in the concealed and protected threaded portions of the device which minimizes the deteriorating effects of weather on these vulnerable parts.

Other objects and advantages will appear from the following description of a preferred embodiment of my invention, reference being made to the accompanying drawing in which:

Fig. 1 is a side elevational view;
Fig. 2 is a front elevational view;
Fig. 3 is a top plan view;
Fig. 4 is a sectional view taken at line 4—4 of Fig. 2, and

Fig. 5 is a transverse sectional view taken at line 5—5 of Fig. 1.

The connector herein shown and described is an improvement of the device described in my Patent No. 2,306,497 of December 29, 1942, and embodies a number of changes which render it especially suitable for use on live overhead lines.

Referring now to the drawing by characters of reference, the connector device of my invention comprises an upper, hood-like body member 10 having an integral depending stem 11. A lower clamping jaw 12 conforms in shape to, and is adapted to fit within the hollow formed in the underside of the body member, the stem or shank portion 11 extending loosely through an elongated opening 13 in the lower jaw. Such stem portion is provided with threads 14, and a clamping nut 15 screws on the threaded stem 11 below jaw 12. The nut 15 has a ring-shaped head portion 16 whereby it is adapted to be attached to and manipulated by a standard tool of a type cus-

tomarily used by linemen for installing tap connectors on live lines. As will appear from Fig. 4, the lower end 17 of the nut bore is of enlarged diameter and the lower end portion of stem 11 is upset to provide a head 18 which limits retraction of the nut 15, and hence the lower jaw 12, to an extent short of complete withdrawal of the jaw from the body cavity. The full retracted position of jaw 12 is shown by broken lines in Fig. 4 and when the jaw is thusly disposed, an opening is presented at the forward end of the assembly which is of sufficient size to admit a wire A laterally into the channel formed between the jaws, yet angular dislocation of jaws relative to each other is prevented.

Describing now the preferred shape of the jaws in greater detail, it will appear that the member 10 is formed to provide a downwardly turned lip 19 at the forward end, and cheek flanges 20 at the sides, such flanges having recesses 21 to receive the wire A and allow it to seat against the inner surface of lip 19. Toward the rear of the body member, the side flanges 20 converge and slope downwardly and outwardly so that an inclined V-shaped channel is formed where these flange portions join together. An opening 22 at top of the body leading from the upper end of the inclined channel, provides a continuous passage through the body so that a wire seating in the channel may extend through the opening 22 and be doubled back as shown. In this manner a tap conductor such as B is adapted to be initially attached to the connector body and held in a position for subsequent clamping.

The lower jaw 12 has a nose-shaped rear end portion, the converging sides of which are inclined in conformity with the angularity and inclination of the body flanges. The sloping ridge of such nose portion extends along and bears against the wire seated in the adjacent channel and such ridge is desirably provided with a longitudinal groove 23 to increase the area of its contact with such wire. At its opposite end, jaw 12 has a downwardly and outwardly sloping beveled surface 24 which faces toward the wire-receiving surface of lip 19, these surfaces coacting to clamp the wire A.

In using the described connector as a live line clamp, as, for example, where a transformer is to be connected in to an overhead line without interrupting the service to other conductors fed from such line, the procedure would be as follows. The nut 15 is unthreaded to the limit of its outward travel on the shank 11, allowing jaw 12 to drop downwardly to full open position. A

tap wire such as B, leading from a primary terminal of the transformer, is initially attached to the connector body 10 by passing the free end of wire B upwardly through opening 22 and bending the end as shown, temporarily to secure the tap wire to the connector. The connector is then installed on the end of a long-handled linesman's tool, a conventional type of which has an end socket to receive the eye portion 16 of the clamping nut. The connector, with the tap wire B trailing therefrom, is then manipulated by means of such a tool so that the lip 19 is caused to be hooked over the line wire A which seats in the transverse channel of the connector body. The tool is then twisted to tighten the nut and force the jaw 12 upwardly into the hollow of the connector body and wedge-wise between the wires A and B. As the jaw is moved upwardly into contact with the wires it is free to shift within the body, as by camming engagement of one or the other of the wires with an adjacent inclined end surface of the jaw. Such shifting movement occurs until the jaw becomes adjusted to a position of solid engagement with both wires. Such shifting of the jaw is possible by reason of the elongated or slotted shape of the opening 13, and is facilitated by the flat and smooth character of the interengaging surfaces of the jaw and nut. It will appear that the wedging clamping action of the jaw 12 with respect to the wires enables high clamping forces to be obtained without the application of unduly high turning forces to the nut. Consequently a tight connection is possible without bending or kinking the line wire. It will also appear that the screw threads on the shank 11 and nut 15 are well protected from the weather so that the normal tendency of these parts to corrode and bond together is minimized. Accordingly, the connector is capable of being removed following a period of service without impairing the device or injuring the line wire.

Having described my invention, what I claim and desire to secure by Letters Patent is:

1. A wire connector of the class described, comprising a body member having downwardly directed side flanges that converge to provide an inclined wire channel at one end of the member, and a downwardly directed lip providing a transversely extending wire channel at the opposite end of the member, a jaw element adapted to fit within the body cavity formed by said flanges and lip, said jaw element having inclined, upwardly convergent end surfaces engageable with wires disposed in said channels, a slotted opening extending through the jaw element, a threaded stem depending from the body through said jaw opening and a nut on said stem for urging said jaw upwardly into wedging engagement with wires seated in said channels.

2. In an electrical connector, a body member having depending flanges at its opposite ends and a depending threaded stem between said flanges, one of said flanges providing a wire seat extending at right angles to said stem, and the opposite flange being formed to provide a channel-shaped wire seat extending at right angles to

the first said wire seat, a clamping element having upwardly convergent wire-engaging surfaces, and an opening between said surfaces, through which opening said stem loosely extends, and a nut threaded on said stem for drawing the clamping element inwardly of the body member and into wedging, clamping engagement with wires disposed in said wire seats.

3. An electrical connector comprising a body member having a threaded stem, and flanges spaced at opposite sides of said stem, one of said flanges providing a wire seat extending at right angles to the axis of said stem, and the other flange being formed to provide a V-shaped wire-receiving channel extending in the plane of, and at an angle to the axis of said stem; a clamping element loosely mounted on said stem and movable therealong into the space between said flanges, said clamping element having sloping, wire-engaging surfaces of converging trend, and a nut on said stem for forcing said clamping element into wedging engagement with wires seating against said body flanges.

4. A wire connector of the class described comprising an upper jaw structure having a downwardly turned lip extending across one end, providing a horizontal wire-receiving channel at the undersurface thereof, the opposite end of the upper jaw structure being formed to provide an inclined wire-receiving channel extending at a right angle to the first said channel, and an opening extending from the upper end of said inclined channel to permit a wire therein to be projected through the top of the upper jaw structure; a lower jaw member having inclined, relatively convergent surfaces adapted to engage wires disposed in said channels, a threaded stem extending vertically from one of said jaw members through an opening between the wire-engaging surfaces of the other jaw member, and a nut on said stem, adapted to force the lower jaw member wedgingly into clamping engagement with wires seated in said channels.

5. A wire connector of the character described comprising a body member having a depending threaded stem, downwardly directed side flanges that converge at one end of the body and provide a downwardly and outwardly sloping wire channel at the junction of their inner surfaces, an opening in the body leading from the upper end of said channel, a downwardly and outwardly directed lip at the opposite end of the body, formed to provide a transversely extending wire channel, a jaw element shaped to fit the cavity in the underside of the body as formed by said side flanges and lip, said jaw element having a longitudinally slotted opening through which said stem portion extends, and upwardly convergent end surfaces for engaging the wires seated in said channels, a clamping nut on said stem seating against the underside of said jaw, and means limiting unthreading of the nut to prevent complete withdrawal of the jaw from said body cavity.

CHESTER R. PIEPER.
